S.E. Taylor,
Fountain Pen.

No 20741.

Patented June 29, 1858.

UNITED STATES PATENT OFFICE.

SUSAN E. TAYLOR, OF EAST CAMBRIDGE, MASSACHUSETTS.

IMPROVEMENT IN FOUNTAIN-PENS.

Specification forming part of Letters Patent No. 20,741, dated October 29, 1858.

To all whom it may concern:

Be it known that I, SUSAN E. TAYLOR, of East Cambridge, in the county of Middlesex and State of Massachusetts, have invented a new and useful Improvement in Fountain-Pens; and I do hereby declare that the same is fully described and represented in the following specification and the accompanying drawing, which exhibits a longitudinal section of a fountain-pen containing my invention.

In such drawing, α denotes a pen-holder constructed tubular, and with a socket β for holding a steel or metallic pen γ . Through the said handle or pen-holder a glass tube δ or ink-fountain is extended, the lower end of the said tube being tapered and furnished with a small discharging-orifice g , arranged close to or against the inner surface of the pen. The upper end of the tube δ is open, so as to enable a piston or plunger h to be passed into the tube. Furthermore, a small hole q is made through the side of the tube δ at a distance from its larger end almost equal to the length of the piston. A slot i is formed in or on the upper end of the piston, in order to enable the piston to be connected to a long wire, which when screwed to it will afford a means by which the piston may be moved longitudinally in the bore of the tube, which constitutes the ink-fountain.

By immersing the lower end of the fountain in a quantity of ink and drawing the piston upward the pressure of the atmosphere will cause the ink to rise in the fountain and will retain it therein until the piston shall be drawn above the orifice g . When this takes place, the external air will pass through the orifice and into the fountain, and in consequence of this the ink will flow out of the lower end or discharging-orifice g . By means of the piston the orifice g can be closed more or less, so as to regulate the amount of air admitted, and of course the amount of ink discharged from the fountain.

The outer case or tubular handle α , I provide with a slot j , extending directly over the orifice g , and a short distance each way, and it in a longitudinal direction; and I so apply

the tube or fountain δ to the handle α as to enable the former to be moved longitudinally with friction within the latter, in order to carry its mouth either nearer to or farther from the point of the pen and retain the fountain in any desirable position within the handle. This enables me to regulate the amount of ink which may gather in the pen, and to place or adjust the discharging-orifice at such distance from the said point as circumstances may require in the proper adaptation of the discharging-mouth of the fountain of the pen, in order that the ink may not be too freely discharged. As my pen-holder is calculated to receive almost any ordinary steel pens, and as pens vary in elasticity, strength, and other properties, it is important that the fountain should be adjustable in the holder as described, the slot j being for the purpose of keeping the orifice g open to the atmosphere under any such adjustment of the fountain.

From the above it will be seen that the piston performs two functions—viz., that of causing the fountain to be charged with ink, and that of a register or valve to the orifice g .

I do not claim a pen combined or provided with a fountain or reservoir stationary within the handle or pen-holder, and having a conduit leading from it in a manner so as to conduct the ink from the fountain to the pen; nor do I claim providing such fountain or reservoir, conduit, and pen with a piston to move in the reservoir; nor do I claim furnishing the fountain with a stop-cock arranged in the conduit and to regulate the supply of fluid to the pen; nor do I claim providing the upper end of the reservoir or fountain with a screw-cap and one or more air-holes so arranged as to be covered by the screw-cap; but

What I do claim is—

1. An improved fountain-pen as made with a pen-holder and a separate adjustable fountain applied so as to be movable with the holder, substantially as and for the purpose as described.

2. When the tubular reservoir is provided with a piston, as described, arranging a small

air-hole *g* through the side of the reservoir, so that the piston, besides being able to perform the office of elevating the ink into the fountain, may be made to cover the air-hole more or less and to operate as a valve to it, substantially in manner and for the purpose as described.

In testimony whereof I have hereunto set my signature.

SUSAN E. TAYLOR.
